Paul Lux, Waterbury, Conn., assignor to The Lux
Clock Manufacturing Company, Waterbury,
Conn., a corporation of Connecticut

Application October 18, 1940, Serial No. 95,912

Term of patent 7 years

To all whom it may concern:

Be it known that I, Paul Lux, a citizen of the United States, residing in the city of Waterbury, in the county of New Haven and State of Connecticut, have invented a new, original, and ornamental Design for Flower Pendulum Clocks, of which the following is a specification, reference being had to the accompanying drawing, forming part thereof.

Fig. 1 is a front view of the flower pendulum clock, showing my new design.

Fig. 2 is a rear view of the same.

Fig. 3 is a side view of the same.

I claim:

The ornamental design for a flower pendulum clock, as shown.

PAUL LUX.
